UNITED STATES PATENT OFFICE

2,520,471

TRAVELER FOR RING TWISTERS

Herbert J. Potts, Pelham Manor, N. Y., assignor
to Alexander Smith & Sons Carpet Company,
Yonkers, N. Y., a corporation of New York

Application July 14, 1949, Serial No. 104,619

2 Claims. (Cl. 57—125)

1

This invention relates to ring travellers for spinning and twisting frames and has for an object to provide a traveller having novel and improved characteristics.

Another object is to provide a traveller of light weight which is capable of exerting a predetermined drag during the spinning or twisting operation.

Another object is to provide a traveller of the above type in which the drag is not dependent upon the friction between the traveller and the ring.

Another object is to provide a traveller which operates with a controlled tension, produces an even twist, introduces a minimum of strain on the yarn as the spindle starts to rotate, and has an improved life.

Various other objects and advantages will be apparent as the nature of the invention is more fully disclosed.

In accordance with the present invention the traveller is made light in weight and is designed to operate on a well lubricated ring with a minimum of friction. In order to cause the traveller to exert the required drag on the yarn it is provided with one or more fins which encounter air resistance to oppose the movement of the traveller on its ring. The size and distribution of the fins is so selected that a predetermined drag is thus introduced which remains constant at any given speed of operation. Hence for a given spindle speed and operating conditions the yarn is wound upon a predetermined, uniform tension and a predetermined amount of twist is imparted thereto.

Since the traveller does not depend for its drag upon its weight or its friction with the ring, the ring may be completely lubricated at all times and the traveller is kept cool both by reason of the lubrication and by reason of the flow of air over the fins.

The nature and characteristics of the invention will be better understood by referring to the following description, taken in connection with the accompanying drawing in which a specific embodiment thereof has been set forth for purposes of illustration.

In the drawing:

Fig. 1 is a side elevation of a spindle and traveller with the ring in section illustrating one embodiment of the invention;

Fig. 2 is a top plan view thereof; and

Fig. 3 is a perspective view of the traveller.

Referring to the drawing more in detail, the invention is shown as applied to a ring 10 form-

2

ing a part of the spinning frame and carrying a traveller 11. The ring 10 is supported by suitable means indicated as a frame 12. The ring 10 is provided with oil grooves 14 and with an upper guiding rim 15 and a lower guiding rim 16 over which the traveller 11 rides.

In the form shown the traveller 11 comprises an inner vertical portion 18 having a U-shaped upper flange 19 and a U-shaped lower flange 20 which seat over the upper and lower guiding rims 15 and 16 respectively of the ring and hold the traveller in place thereon during the spinning operation. Air fins 22 and 23 are carried by the upper and lower flanges respectively and are disposed transversely with respect to the direction of movement of the traveller so as to produce a predetermined air resistance as the traveller rotates rapidly around its ring.

The yarn 30, which is being spun or twisted, 20 is passed under the upper flange 19 of the traveller and thence onto a winding 31 on a spool or bobbin 32 mounted on a spindle 33 which is rotated and reciprocated vertically in the usual manner.

25 During the spinning or twisting operation the traveller 11 is caused to rotate rapidly around the ring 10 in a well known manner. The traveller, however, exerts a predetermined drag on the yarn 30 which is being wound on the bobbin 32. This drag remains constant during the winding operation. Hence the yarn may be wound under a predetermined tension to form a compact package on the bobbin.

30 Among the advantages of the present invention are greater wear life for both the ring and traveller due to improved lubrication which results in the cooler running of the traveller and consequently fewer changes of the traveller are required. It is also possible to operate at increased spindle speed thereby further increasing the production. The controlled tension results in an even winding on the spool or bobbin with a uniform twist. The breakage of the yarn particularly during the starting of the spindle, is reduced inasmuch as the traveller may be made comparatively light thereby reducing its inertia and correspondingly reducing the strain on the yarn as the spindle starts to rotate. A further advantage resides in the reduction of the number of different weights of travellers that must be kept in stock.

35 Obviously the air fins may be disposed in different locations on the traveller. In the form shown the top and bottom fins provide a balanced operation and are designed to exert sub-

stantially the same drag at the top and bottom thereby reducing the tendency for the traveller to tilt over and drag or bind on the rims of the ring during operation.

What is claimed is:

1. A spinning or twisting frame for yarn comprising a rotating spindle, a traveller ring disposed thereabout, and a traveller riding on said ring, said traveller having upper and lower flanges disposed to guide the same on said ring, and fins disposed on said upper and lower flanges and extending in a direction transverse to the direction of movement of said traveller around said ring to introduce air resistance to the movement thereof.

2. A traveller for a ring twisting or spinning frame comprising a vertical member adapted to span said ring and having upper and lower flanges

positioned to extend over the top and bottom rims respectively of said ring for guiding the traveller therearound, said traveller having an upper fin projecting upwardly from the upper surface thereof and a lower fin projecting downwardly from the lower surface thereof, said fins being disposed to introduce air resistance to the movement of said traveller around said ring.
